UNITED STATES PATENT OFFICE.

NICHOLAS WADDELL CEASE, OF SCHENECTADY, NEW YORK.

DISHWASHING MACHINE.

Application filed May 4, 1922. Serial No. 558,462.

This invention relates to a dish washing machine, the general object of the invention being to provide rotating sprayer arms which will throw the water upon all parts 5 of the dishes from a point below the supporting racks for the dishes with means for forcing through the arms washing water and rinsing water.

Another object of the invention is to provide a pump for drawing the water from the bottom of the washer and forcing it through the arms, with means whereby the pump can be used for draining the device.

Another object of the invention is to provide a pair of spraying devices with valve means for admitting the water to both devices simultaneously or to either one, as desired, such valve means also controlling the connection to the pump and to the supply 20 pipe.

This invention also consists in certain other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:

Figure 1 is an elevation of the invention.

Figure 2 is a side view, with parts in 35 section.

Figure 3 is a section on line 3—3 of Figure 2.

Figure 4 is an enlarged longitudinal sectional view, with parts in elevation, showing 40 the sprayer arms and their stand pipes.

Figure 5 is a section on line 5—5 of Figure 4.

Figure 6 is a section on line 6—6 of Figure 4.

Figure 7 is an enlarged sectional view 45 through the valve means.

Figure 8 is a section on line 8—8 of Figure 7.

Figure 9 is a section on line 9—9 of Figure 50 7.

Figure 10 is a section on line 10—10 of Figure 7.

Figure 11 is a plan view of the sprayer arms.

Figure 12 is a view showing how the device can be combined with a kitchen sink.

Figure 13 is a sectional view showing means for connecting the pump directly with the stand pipes.

Figures 14 to 31 inclusive are sectional 60 views showing the various positions of the valve core.

In these views 1 indicates the tank which is supported by the legs 2 and which is provided with a cover 3. Dish supporting racks 65

4, of any suitable construction, are arranged in the tank, these racks being supported upon the brackets 5 so that they can be easily lifted out of the tank when desired. The 70

bottom of the tank slopes towards the center where an opening is formed which is closed by the upper end of a hollow body 6 which is connected by the passages 7 and 7'

with the valve casing 8. This body may be bolted to the bottom of the tank and it is 75

formed with three chambers 9, 10 and 11, the chambers 10 and 11 being in communication with the passages 7 and 7' and the chamber 9 is connected with the chamber 10 by a screw threaded bore 12 and the chamber 10 with the chamber 11 by a screw 80

threaded bore 13 which is of smaller diameter than the bore 12. The chamber 11 is of larger diameter than the bore 13 and the chamber 10 is of larger diameter than the bore 12. A stand pipe 14 has its lower end 85

screw threaded to engage the bore 12 and a stand pipe 15 has its lower end screw threaded to engage the bore 13, the pipe 15 passing through the pipe 14 and being of 90

much smaller diameter than said pipe 14 so as to leave a space between itself and the inner wall of said pipe 14. The pipe 15 is of greater length than the pipe 14 with its upper end passing through a hole in the top 95

of pipe 14. Sprayer arms 16 and 17 are arranged to rotate on the pipes 14 and 15, the arms being provided with hollow hubs 18 and 19 for engaging said pipes, the hub 18 resting upon a shoulder 20 formed on the 100

pipe 14 and the hub 19 resting upon the top of said pipe 14. Each pipe is provided with openings 21 which communicate with the interior of the hubs so that liquid passing 105

through the pipes 14 and 15 will enter the hubs and the arms. Each hub carries a pair of arms which are diametrically opposite each other and the perforations 22 in the

arms are inclinedly arranged so as to cause the action of the water passing through the perforations to revolve the arms and the hubs upon the stand pipes. The perforations in one set of arms are oppositely arranged to those in the other set so that one pair of arms will revolve in one direction and the other pair in an opposite direction. The outer end of each arm may be provided with a nozzle 23. These arms are arranged below the racks for the dishes and the perforations are formed in the upper part of the arms so that the spray will be directed upwardly against the dishes and as one pair of arms is revolved in one direction and the other pair in an opposite direction the spray will strike all parts of the dishes to thoroughly cleanse the same. As shown, the lower end of the pipe 14 is in communication with the chamber 10 and the lower end of the pipe 15 with the chamber 11, said chambers being connected with the valve casing, as before stated, so that the valve will control the flow of water into the stand pipes. The valve shell 24 is of tapered shape, the interior of the valve casing being of similar shape, and said shell is held in tight connection with the interior walls of the casing by a spring 25. The stem 26 of the valve is connected with a handle 27 by a flexible joint 28. The shell 24 is provided with four ports 29, arranged a quarter turn from each other, which are adapted to connect the interior of the shell with the passage 7 leading to the chamber 11. The shell 24 is also provided with a pair of ports 30, diametrically opposite each other, which are arranged to connect the interior of the shell with the passage 7 leading to the chamber 10. The central part of the shell is provided with a large port 31 which is associated with the nipples 32 and 33 on the valve casing, the nipple 33 being connected with a pipe 34 which is connected with a source of supply and the nipple 32 is connected with a pipeline 35, this pipe line being connected with a pump 36 and with a discharge pipe 37. The inlet of the pump is connected with the chamber 9 of the body 6, as shown at 38. The pump may be operated by a motor 39, the switch for controlling the circuit of which being shown at 40. A valve 41 may be placed in the outlet end of the line 35, said valve being controlled by a foot lever 42 and the exhaust pipe 37 may be provided with a suction cup 43 which is adapted to be placed over the drain of the sink 44, for instance, so that the tank may be drained by siphon action after it has been partly drained by the pump. Of course the exhaust pipe 37 may be connected with any suitable discharge pipe.

Figure 12 shows the apparatus combined with a sink, the top 3' of the tank forming

the drain board of the sink, the inlet pipe 34 being connected with the hot water pipe 34' of the water system and the exhaust pipe 37 being connected with the goose neck 37' of the drain for the sink.

I may also connect the pump directly with the stand pipes so that a valve is not necessary. For instance, the passages 7" of the body 6' shown in Figure 13 can be connected directly to the discharge of the pump so that as soon as the pump begins to operate water will flow through the passages into the chambers 10' and 11' and thus into the stand pipes and through the sprayer arms.

Where the device is attached to the city main the valve is adjusted so that the water will flow through the pipe 34, through the valve means and its connections with the pump, through the pump, which is stationary, into the chamber 9 and the tank through the connection 38. When a sufficient amount of water has entered the tank, the valve is adjusted to connect the pump with both the passages 7 and 7' or either one of said passages and then the switch is turned to supply current to the motor. The pump will then draw the water from the bottom of the tank and force it through the valve means, the passages 7 and 7' into the chamber 10 and 11 and up through the stand pipes to the sprayer arms. The water will be thrown by said arms against the dishes and then the water will drop back to the tank from which it will again be drawn by the pump so that the pump will cause the water to circulate through the parts of the device until the dishes are thoroughly cleansed. As before stated, the valve means may be set so that the water will only pass into one of the stand pipes. When this is done one set of arms will remain stationary while the second set is revolving. Water can be supplied to either set by the valve means. After the dishes are washed they may be sprayed with cleansing water by setting the valve means to connect the supply pipe 34 with one or both stand pipes.

Figures 8, 9 and 10 show the position of the valve core 24 to admit water from the pump into passage 7' and thence to the stand pipe 15, while Figures 14, 15 and 16 show the position of the valve core to admit water from the pump into passage 7 and thence to the standpipe 14. To admit water from the pump to both passages 7 and 7', the valve core is turned to the position shown in Figures 20, 21 and 22. To admit water from the supply pipe 34 to the passage 7' the valve core is turned to the position shown in Figures 17, 18 and 19, to admit water from the supply pipe to passage 7 the valve is turned to the position shown in Figures 26, 27 and 28, and to admit water to both passages 7 and 7', the valve core is turned to the position shown in Figures 23, 24 and

25. To supply water from the pipe 34 directly through the pump, the valve core is turned to the position shown in Figures 29, 30 and 31.

5 The tank can be drained by opening the valve 41 through the foot pedal 42 and actuating the pump for withdrawing the water from the bottom of the tank and forcing it through the pipe 37. After water begins to flow through the pipe 37 the pump can be turned off as the siphon action of the water flowing through the pipe 37, the cup 43 and the drain pipe will act to withdraw the remaining water in the tank therefrom.

15 In places where a water supply is not available the tank can be filled by hand and the pump used to circulate both the washing water and rinsing water.

As will be seen the valve can be adjusted 20 to cause the water from pipe 34 to pass through the pump, or the passage 7, or the passage 7' or through both passages. The valve means can also be adjusted to cause the pump to circulate the water through 25 both passages or either passage and said valve means may be set to close both passages and the pipe 34 so that the pump can be used for draining the tank.

When it is desired to cleanse the device 30 more thoroughly the racks will be lifted out and the sprayer arms lifted off the stand pipes and reversed so that the perforations point downwardly. Then when the device is started up the spray water will strike the 35 sides and bottom of the tank and clean the same. The stand pipes can easily be removed by unscrewing them from the body 6 so that all the parts can be thoroughly cleaned in the minimum amount of time.

40 The arrangement of the sprayer arms will cause the water to strike all parts of the dishes so that they are thoroughly cleaned and rinsed.

45 It is thought from the foregoing description that the advantages and novel features of my invention will be readily apparent.

I desire it to be understood that I may make changes in the construction and in the combination and arrangement of the several parts, provided that such changes fall 50 within the scope of the appended claims.

What I claim is:—

1. A dish washing machine comprising a 55 tank, supporting means for the dishes in said tank, a plurality of revolving spraying devices in said tank arranged to throw the spray in the direction of said supporting means, means for supplying a liquid to said spraying devices, and a selective valve device for shutting off the supply of liquid or for admitting liquid to any one of said spraying devices separately or to a plurality of said spraying devices as desired.

2. A dish washing machine comprising a 60 tank, supporting means for the dishes in

said tank, a plurality of revolving spraying devices in said tank arranged to be driven in opposite directions, and a single valve means for supplying a liquid to any one of said spraying devices singly or to all of said spraying devices as desired.

3. A dish washing machine comprising a tank, supporting racks for the dishes in said tank, a plurality of sprayer arms below said racks having their orifices arranged to throw 75 the spray upwardly and to cause said arms to rotate in opposite directions, and means for supplying a liquid to a part or all of said arms as desired.

4. A dish washing machine comprising a 80 tank, a number of concentric stand pipes centrally located in said tank, a sprayer arm carried by each pipe, liquid supplying means connected with the pipes and valve means for causing the liquid to pass to all the pipes 85 or to any pipe, as desired.

5. A washing machine comprising a tank, a pair of stand pipes in the tank, one stand pipe being located in the other, a sprayer arm carried by each pipe, means for circulating the water through the tank and the stand pipes and valve means for causing the water to pass through both pipes or any pipe 90 as desired.

6. A dish washing machine comprising a 95 tank, a supporting rack for the dishes in said tank, tubular upright supporting means centrally located in said tank having its upper end closed, means for supplying water 100 to said supporting means, a pair of hubs of different sizes on said supporting means, the smaller hub being adjacent the upper end of said supporting means, a bearing flange on the lower end of the larger of said hubs, a plurality of spraying devices provided with bores fitting on said hubs, one 105 of said spraying devices resting on the upper end of said larger hub, said supporting means being provided with ports communicating with the interior of said spraying devices and said spraying devices being secured in place by their own weight so as 110 to be freely removable to be reversed to throw the water in either an upward or downward direction.

7. A washing machine comprising a tank, a hollow body connected with the lower end of the tank, a plurality of pipes in said tank, said pipes having their ends screw threaded in said body, one pipe being located in the other, sprayer arms having hollow hubs movably engaging the upper ends of the pipes and means for feeding water to the hollow body to cause it to pass through the pipes into the arms.

8. A washing machine comprising a tank, a pair of stand pipes therein, a sprayer arm rotatably connected with each pipe, a pump connected with the bottom of the tank and valve means for connecting the 120 125 130

pump with both stand pipes or with either one.

9. The combination with a washing machine, of a flexible discharge pipe therefor, a suction cap on said discharge pipe arranged to fit tightly on a sink drain, and a pump for starting the discharge of liquid from the washing machine through said pipe whereby the washing machine is thereafter emptied by siphon action.

10. A washing machine comprising a tank, a pair of spraying devices therein, a valve

casing, a supply pipe connected with the casing, a pump connected with the casing and with the bottom of the tank, and a valve core in the casing provided with a plurality of ports arranged so that the supply pipe may be connected with the pump or with one or both spraying devices and the pump connected with one or both spraying devices, and an exhaust pipe connected with the pump.

15 20
In testimony whereof I affix my signature.
NICHOLAS WADDELL CEASE.
